UNITED STATES PATENT OFFICE.

HERBERT F. PLUMB, OF DRUMHELLER, ALBERTA, CANADA.

CALL ANNUNCIATOR.

1,418,969.

Specification of Letters Patent. Patented June 6, 1922.

Application filed October 15, 1918. Serial No. 258,177.

To all whom it may concern:

Be it known that I, HERBERT F. PLUMB, a subject of the King of England, residing at Drumheller, in the Province of Alberta and 5 country of Canada, have invented certain new and useful Improvements in a Call Annunciator, of which the following is a specification.

This invention relates to an improved call 10 annunciator or electrical indicator designed to give a visual as well as an audible signal, so that a person who has heard a signal can positively ascertain the exact signal which is given, thereby ensuring accurate carrying 15 out of the order for which the signal stands.

A further object of the invention is to provide a call annunciator or electrical indicator of this character, which is electrically operated and designed for use in mines to indicate 20 when an elevator is to be hoisted or calls for coal, men or otherwise, or which can be applied to various other uses where an annunciator of this character is usable, the device positively communicating the signal 25 visually and being capable of operation electrically, as well as constructed in a manner quite novel and capable of being released so that it is returned to an inoperative position after each signal is given, thereby permitting 30 its immediate re-use and avoiding errors which might otherwise occur.

With the above objects and others in view as will appear as the description proceeds, the invention comprises the novel features of 35 construction, combinations of elements and arrangement of parts which will be more fully described in the following specification and embodied in the claim which is appended hereto.

40 Reference is had to the accompanying drawing forming a part of this application, wherein similar reference characters will refer to corresponding parts throughout the several views, in which—

45 Figure 1 is a diagrammatic elevation showing my improved call annunciator or electrical indicator, and

Figure 2 is an enlarged vertical view 50 transversely of the device and showing the operative parts.

Figure 3 is a sectional view taken on the line 3—3 of Fig. 2.

55 Referring to the drawings in detail, my improved call annunciator or electrical indicator comprises a base or backboard 10 preferably of non-conducting material and

is suitably mounted or supported at the place where it is desired to give the signal. Slidably supported thereon as by means of 60 guide straps 11, is a vertical indicator bar 12 having formed at the upper end thereof, a pointer 13 designed to cooperate with a series of indications 14 equally spaced apart and marked as shown at 15, to indicate the 65 number of bells or annunciations given audibly as will be hereinafter set forth. The bar 12 is provided upon its outer face with a series of ratchet teeth 16, the upper faces of which are beveled downwardly as indicated at 17, thereby providing substantially horizontally 70 positioned lower faces 18 to facilitate the raising and lowering of the bar as will be further explained.

Mounted on the base 10 upon a horizontal 75 and slightly inclined pivot 19 for movement in an inclined plane, is a detent 20 adjacent at the free end of which there is positioned a pair of electro-magnets 21, the detent serving as an armature and being of such material as to be magnetically effected so as to 80 be drawn toward the magnets when the latter are energized so as to cause the detent to engage over one of the beveled faces 17 and beneath the adjacent face 18 of a tooth 16 to raise the bar 12 one step at a time. This 85 part of the mechanism serves to operate the visual signal in conjunction with an electrical circuit for controlling the magnets, as will be further explained.

The releasing mechanism for the slidable 90 bar 12 to permit the same to be lowered and returned to its normal, initial position comprises a spring catch 22 which is secured to the base 10 as at 22^a and coiled in substantially U-shaped form so that the free end 95 22^b may engage beneath one of the teeth 18 to be withdrawn therefrom. Mounted on the base 10 and to one side of the spring catch, I have provided an electro-magnet spring support 23 carrying a pair of electro-magnets 24 positioned so that when energized, they will attract the armature or bar 25 pivoted or hinged at 25^a to said base and suitably connected to and near the free end 100 of the spring catch 22 whereby the same may be released from the slidable bar and permit said bar to drop by gravity to its initial position, the pointer 13 of said bar thus returning to the bottom of the scale as is readily understood and as clearly shown by 110 Fig. 2 of the drawing.

The electro-magnets or solenoids 21 are

connected in circuit with a source of electrical energy such as storage batteries or the like, indicated at 26, through the medium of a conductor 27, leading to one pole of the 5 source of energy, the circuit being completed through a conductor 28 with an interposed push button or other switch 29. Connected in the circuit with the electro-magnets 21 is an audible signal or bell 30, a branch conductor 31 leading from the conductor 27 to one pole of the bell or binding post thereof, and a branch conductor 32 leading from the other binding post to the conductor 28 so that upon the switch 29 being closed, the 10 circuit will be closed through the electro-magnets 21 to energize the same and thereby attract the armature forming detent 20 to raise the bar 12 a single tooth and correspondingly move the indicator pointer 13 15 along the indications 15 to visually indicate the call, as well as audibly indicate the same.

The releasing device is connected in the circuit with batteries to be independently operated for releasing the bar to permit it to 20 be dropped to initial or normal position and for this purpose the electro-magnets or solenoids 24 are connected by a conductor 33 with the source of electrical energy at one side and through a conductor 34 with the opposite pole of the battery or source of electrical energy. The conductor 34 is provided with an interposed push button or other type of switch as at 35 which upon being closed, will close the circuit through the batteries 30 and magnets 24 to detract the spring catch 22 by the energization of the solenoids, thereby releasing the bar by withdrawing the catch from the teeth thereon. The bar will be capable of downward movement as 35 long as the catch is held withdrawn, but it is to be understood that the bar will be elevated one step at a time each time the circuit through the switch 29 is closed to simultaneously operate the visual and audible 40 signals thereby imparting a step by step 45

movement to the indicator or pointer 13 according to the indications or markings indicated at 14 and 15, as compared with the signal desired to be given for a particular purpose. For convenience, a chart may be 50 arranged adjacent to the call and receiving ends so as to ensure correct sending and answering of signals. In this way, when a signal is given, should a person hear the same but not be sure of the number of signals given, the visual annunciator can be resorted to. It is also to be understood that the detent 20 when released, will permit free downward movement of the bar upon disengagement of the spring catch 22 as explained, since the detent 20 will be out of the path of the teeth 16 of the bar. The device is especially adapted for use in mines, where code signalling by a bell is generally employed.

Having thus fully described my invention, what I claim as new, and desire to secure by Letters Patent of the United States, is:

A call annunciator comprising a bar, an insulated base on which said bar is slidably supported for vertical movement, said bar having teeth and provided with a pointer, spaced indications on said base with which said pointer cooperates, a detent engageable with the teeth of the bar to raise the same 75 one step and normally disengaged therefrom, an electro-magnet for actuating the detent, a spring catch having one end attached to the base and its opposite free end engaging the teeth of said bar, an armature mounted 80 on said spring near the free end thereof, and a second magnet attached to said base co-operating with said armature to withdraw the free end of the spring from engagement with the teeth of the bar to permit said bar 85 to fall by gravity.

In testimony whereof, I affix my signature hereto.

HERBERT F. PLUME.
